CLAIM

The ornamental design for a golf training mat, as shown and described.

DESCRIPTION

FIG. 1 is a top isometric view of the golf training mat.
FIG. 2 is a bottom isometric view of the golf training mat of FIG. 1.

FIG. 3 is a front elevation view of the golf training mat of FIG. 1.

FIG. 4 is a side elevation view of the golf training mat of FIG. 1.

FIG. 5 is rear elevation view of the golf training mat of FIG. 1.

FIG. 6 is another side elevation view of the golf training mat of FIG. 1.

FIG. 7 is a top plan view of the golf training mat of FIG. 1; and,

FIG. 8 is a bottom plan view of the golf training mat of FIG. 1.

The evenly dotted broken lines in the drawings illustrate unclaimed features of the golf training mat and form no part of the claimed design. The dash-dot-dash broken lines in the drawings represent borders of unclaimed portions of the golf training mat and form no part of the claimed design. Portions of the claimed design are shown separated and bound by a bracket to indicate indeterminate length.
